UNITED STATES PATENT OFFICE.

HANS SCHLICHT, OF WALNUT, IOWA.

PLOW.

1,113,494.

Specification of Letters Patent.

Patented Oct. 13, 1914.

Application filed May 26, 1913. Serial No. 770,060.

To all whom it may concern:

Be it known that I, HANS SCHLICHT, a citizen of the United States, and resident of Walnut, in the county of Pottawattamie and State of Iowa, have invented a certain new and useful Plow, of which the following is a specification.

The object of my invention is to provide a gang plow of comparatively simple construction, provided with mechanism so constructed and arranged that the plows may be moved closer to each other or farther apart from each other, as desired.

More particularly it is my purpose to provide such a plow, in which the plow shares may be manipulated as above set forth for turning corners.

Still a further object is to provide a plow of the class mentioned in which an additional share is carried for throwing a land while turning corners so that after a few rounds have been plowed the curve of the furrows at the corners forms the arc of a comparatively large circle.

Still a further object is to provide in such a plow, means whereby the distance of the plow shares from each other is automatically regulated during the plowing of a "land."

My invention consists in certain details, in the construction, combination and arrangement of the various parts of the device whereby the objects contemplated are attained, as hereinafter more fully set forth, pointed out in my claims and illustrated in the accompanying drawings, in which:

Figure 1 shows a side elevation of a plow, embodying my invention. Fig. 2 shows a top or plan view of the same, Fig. 3 shows a detail view of the mechanism for automatically regulating the distance of the plows from each other, and Fig. 4 shows a detail view showing the manner in which the arm 63 is jointed.

In the accompanying drawings I have used the reference numeral 10 to indicate generally the main frame of my plow. Extending forwardly from the front end of the main frame is an additional frame 11. Pivoted to the portion 11^a of the frame 11 is a sleeve 12 which carries the axle 13 on which are the front wheels 14. Suitably mounted upon the frame 10 is a rear axle 15 on which are mounted large traction wheels 16.

Mounted upon the frame 10 is a suitable, primary source of power 17 which may be a

gasoline engine or the like. Upon the engine shaft 18 is a friction wheel 19 carrying a friction band 20. Suitably mounted upon the frame 10, near the sides thereof is a shaft 22 on which are slidably mounted friction disks 23 and 24, designed to be in one position of their respective movement in engagement with the band 20 on the wheel 19. Rotatably mounted upon the frame 10 is a shaft 25 upon which is a pinion 27 which is in mesh with the pinion 29 on the shaft 22. Upon the axle 15 are sprockets 30 and upon the shaft 25 are adjustably mounted sprockets 31 by means of the sleeves 32 and set screws 33. The rear axle is designed to be of the two part type, described in my application for patent, filed April 15, 1912, Serial No. 690,893. Upon the sprockets 30 and 31 are sprocket chains 31.

For throwing the friction disks 23 and 24 respectively into or out of gear with the band 20 on the wheel 19, I have provided the following means. Formed on the disks 23 and 24 are sleeves 23^a and 24^a. Pivoted to the sleeves 23^a and 24^a are one arm of a bell crank lever 34, which lever is centrally pivoted on the frame of the machine. Pivoted to the other arm of said lever 34 is a rearwardly extending link 36, the rear end of which is pivoted to a controlling lever 38. Pivoted to the sleeves 23^a and 24^a is a lever 35 which is pivoted at a point between its ends on the frame and has a rearwardly extending handle 37. It will be understood that the levers 34 and 35 are so connected with the sleeves 23^a and 24^a as to permit the free rotation of said sleeves with the shaft 22. By manipulating the levers 38 and 35, the sleeves 23^a and 24^a and the disks 23 and 24 may be moved inwardly or outwardly on the shaft 22.

The wheel 19 is slidably but non-rotatably mounted upon the shaft 18. For sliding the wheel 19 toward and away from the center of the disks 23, I have operatively connected with the hub 47 of the wheel 19 a link 48 which is in turn pivoted to one end of the lever 49. The lever 49 is centrally pivoted on the frame of the machine and is pivoted at its other end to a link 50. The link 50 is operatively connected with a suitable lever 51.

Mounted on the engine shaft is a friction wheel, which may be in engagement with the disk 41 slidably mounted on the longitudinally arranged shaft 42. For sliding

the disk 41 on the shaft 42 and thereby throwing it into or out of engagement with the wheel 40 I have pivoted on the disk 41 a link 43 which is also pivoted to a lever 44.

- 5 The lever 44 is centrally pivoted on the frame 10. Pivoted to the end of the lever 44, opposite to the end thereof to which the link 43 is secured, is a link 45, which is in turn pivoted to a controlling lever 46.
- 10 Pivoted to the frame, near the rear end thereof, is a lever or bar 58 which is normally arranged with its longitudinal axis forming an obtuse angle with the longitudinal axis of the machine, as shown in Fig. 3.
- 15 At one end of the lever or bar 58 is a right angled rearward extension 59. Near the other end of the lever or bar 58 is pivoted a short link 60. Plow beams 52 are pivoted to the link 60, to the extension 59 and to the central part of the bar 58. Pivoted to the end of the bar 58, opposite that on which the extension 59 is formed, is a link 60^a which extends forwardly in the machine. Mounted on the beams 52 are plow shares 53. The beams are adjustably connected by bars 52^a, which are pivoted to the respective beams and are adjustable with relation to each other.

The plows are arranged in gangs, each 30 plow except the front one being in the rear of the plow next in front. Secured to each of the plow beams 52 is a chain or other flexible device 57. The chains 57 are wound upon a transverse shaft 54. Upon the shaft 35 54 is a ratchet 101, and upon the frame 10 is mounted a pawl 102, arranged to coact with the ratchet for holding the plows up. Upon the shaft 54 is a beveled gear 55 in mesh with the beveled gear 56 on the shaft 42. 40 By throwing the disk 41 into engagement with the disk 40, the shaft 42 may be rotated for raising or lowering the plows by winding or unwinding the chains 57 on the shaft 54. Pivoted to the sleeve 12, on the 45 front axle to the left of the center thereof, as shown in Fig. 3, is an inwardly extending arm 61 to which the link 60^a is pivoted. Pivoted to the sleeve 12, near its right hand end is a forwardly extending arm 62 to 50 which is pivoted to an arm 63 which normally extends forwardly and is also inclined laterally to the right. At the forward end of the arm 63 is a downwardly extending portion 64 on which is mounted a roller 65. 55 The arm 63 is pivoted to the arm 62 at 66 to permit the arm 63 to swing upwardly and downwardly to prevent lateral movement of said arms with relation to each other, and to limit the downward movement of said 60 arm 63 a link 67 is pivoted to the arm 62 and the arm 61.

It will be seen that in the machine, as shown in the drawing, if the arm 63 is moved it will move the right hand end of 65 the bar 58 forwardly or rearwardly and

thereby move the parts 59 and 60 toward or away from the central, longitudinal line of the machine. The effect of said movement, during the operation of the machine would be to cause the plows to move toward or 70 away from the middle of the machine. The wheel 65 is designed to travel in the furrow and engage the side thereof. On account of the fact that the arm 61 is secured to the sleeve 12 at a point apart from the middle 75 thereof, the draft of the plows would tend to draw the left hand front wheel rearwardly and cause the machine to turn. To overcome this tendency, I have secured to the sleeve 12, at a point spaced apart from 80 the middle thereof, at the right hand side, a contractile coil spring 68, which is, in turn, secured to the frame 10. For normally drawing the arm 62 inwardly and thereby causing the wheel 65 to engage the land at 85 the side of the furrow, a contractile coil spring 69 is secured to the arm 62 and to the sleeve 12, as clearly shown in Fig. 3.

Upon the frame 10 is mounted a bracket 70 in which is slidably mounted a vertical 90 bar 71, which carries a plow share 72. Mounted on the frame 10 is a bell crank lever 73, one end of which is pivoted to a link 74. The link 74 is pivoted to the bar 71. Secured to the other end of the bell 95 crank lever 73 is a flexible device or chain 75, one end of which is wound around the shaft 54. It will be understood that ordinary steering mechanism may be used on my plow for controlling the front wheels. 100 A differential may be used which may be of any ordinary construction.

In the practical operation of my improved plow, when the machine is to be drawn over ordinary ground, the engine is started and 105 the members 40 and 41 are thrown into engagement. The plows may be raised and said members may then be moved out of engagement. The lever 51 and mechanism connected therewith may be operated to move the wheel 19 to a point almost opposite the center of the friction disks. One of said disks may then be moved by means of the proper mechanism hereinbefore described into contact with the friction band 20 and 110 the chain will be propelled forwardly or rearwardly, depending upon which of the disks 23 or 24 has been thrown into gear. By sliding the wheel 19 upon the shaft 18, any desired speed of the machine may be 115 obtained.

As hereinbefore explained, it is my desire to provide a machine in which a single land may be plowed from the outside by throwing a substantially continuous furrow. 120 In plowing a field, I plow once around the entire field, throwing the land toward the outside. On the second round, the plow 72 will travel in the open furrow and will be inoperative until the corners are reached. 125 130

On going around the corner, the plows 53 will tend to swing together. On the other hand, as the front axle is turned, the left side thereof will move rearwardly toward 5 the rear axle permitting the arm 61 and the link 60^a to move rearwardly. This will move the pivotal points where the outer plows are connected to the bar 58 a slight distance farther from the middle line of the plow 10 than their ordinary position and will tend to hold the plows apart. The plows 53, however, tend to swing inwardly from the furrow and to leave an unplowed space. As this occurs, the plow 75 enters the ground 15 and cuts out the land that would ordinarily be unplowed at the corner. After this operation has been repeated several times at each corner, a curved furrow is made at each corner instead of one having a substantially 20 square corner. The land may then be plowed in one great circle until the field is completed.

On account of the construction of the parts heretofore described, the plow will 25 practically guide itself after the first round. The wheel 65 will engage the side of the furrow and will properly steer the plow. The advantage of a device of this kind can readily be seen. After a few rounds, a wide 30 curve is made at the corners so that the rest of the field may be plowed without any sharp turns. It will be seen that with my improved plow, the field may be completely turned over and this may be accomplished with a minimum packing down of 35 the plowed ground.

The important parts of my device are of comparatively simple and inexpensive construction and my plow can be built at a comparatively small expense. After the first 40 round it is practically self guiding.

I believe I have produced a very effective transmission mechanism in the arrangement of the wheel 19 on the shaft 18 and in the 45 placing of the friction band on the wheel on the engine shaft. By this arrangement I do away with the danger of the flat spot in the friction band which often causes trouble with the ordinary forms of friction disk 50 transmission.

I claim as my invention:

1. In a device of the class described a frame, a front axle centrally pivoted thereon, a bar centrally pivoted on said frame, a 55 plurality of plows having their beams piv-

oted to said bar, an arm on said front axle spaced apart from the middle thereof, a link connecting said arm and said bar, yielding means secured to said frame and to said front axle on the side thereof opposite said 60 arm for overcoming the draft of said plows, an arm pivoted to said front axle near one side thereof and carrying a wheel designed to engage the land in a furrow, and a link connecting said last named arm and said 65 first named arm.

2. In a device of the class described, a frame, plows pivoted thereto, and means whereby said plows are automatically moved farther apart when the device is turning 70 a corner and are returned to normal position when the device once more travels in a direct line.

3. In a device of the class described, a frame, a plurality of plows pivoted thereto, 75 and means whereby said plows are automatically moved apart from each other when the device is turning a corner.

4. In a device of the class described, a frame, a plurality of plows pivoted thereto, means whereby said plows are automatically moved apart from each other when the device is turning a corner, and means whereby said plows may be raised or lowered.

5. In a device of the class described, a 85 frame, a plurality of plows pivoted thereto in a gang, means whereby said plows are automatically moved apart from each other when said device is turning a corner, an additional plow mounted on said frame near 90 the forward end thereof, means whereby said plows may be raised or lowered, said plows being so arranged that on turning a corner said additional plow enters the ground while in ordinary straight plowing 95 it travels in the last furrow.

6. In a device of the class described, a frame, a plurality of plows mounted thereon in a gang, an additional plow mounted on said frame, and mechanism whereby said additional plow may be lowered to operative 100 position while the device is turning a corner and raised when the device once more travels in a straight line.

Des Moines, Iowa, April 18, 1913.

HANS SCHLICHT.
